CLAIM

The ornamental design of the foldable bottle with bubble pattern, as shown and described.

DESCRIPTION

A portion of the disclosure of this patent document contains material which is subject to copyright protection. This patent document may show and/or describe matter which is or may become trade dress of the owner. The copyright and trade dress owner has no objection to the facsimile reproduction by anyone of the patent disclosure as it appears in the Patent and Trademark Office patent files or records, but otherwise reserves all copyright and trade dress rights whatsoever.

The sole FIGURE is a front perspective view of the foldable bottle with bubble pattern showing my new design.

A dashed line outlines the extent of the bubble pattern. The dashed line is not a part of the claimed design. Additional broken lines show a foldable bottle for illustration purposes only, and do not form a part of the claimed design.
